ARTICLE CLEANING MECHANISM

Otto C. Niederer, Otto Niederer, and Herbert O. Niederer, Titusville, N. J.

Application February 18, 1949, Serial No. 77,096

18 Claims. (Cl. 51—138)

1

Our invention relates to methods and means for cleaning, abrading, brushing, polishing or similarly treating rounded articles and while our invention is of general application, it is particularly adapted for use in cleaning eggs.

Many eggs when collected by poultrymen or farmers are soiled or stained and therefore are unattractive in appearance and cannot be marketed to advantage until they are cleaned. However, the operation of cleaning eggs by hand is tedious and the large number of eggs that require cleaning frequently renders manual cleaning uneconomical. On the other hand, the irregularity in size and shape of eggs and the varying texture and condition of egg shells does not permit them to be cleaned readily or safely by ordinary brushing or abrading devices, whereas egg washing operations have been known to cause eggs to rot or spoil within a few days.

In accordance with our invention these problems are overcome by providing mechanism whereby eggs and other articles may be brushed, abraded, polished or otherwise treated by the action of flexible abrading means which are brought into contact with all points on the surface of the articles so as to clean the article without injury thereto. Moreover, the eggs or other articles to be cleaned are presented to the abrading members in such a way that different sizes of eggs may be cleaned simultaneously and they may be supplied to and removed from the mechanism continuously so that repeated or individual handling of the eggs is not necessary.

One of the objects of our invention is to reduce the cost and increase the speed with which eggs or other rounded articles may be cleaned.

Another object of our invention is to provide mechanism whereby eggs and similar articles may be continuously and automatically supplied to and removed from yieldable abrading members.

Another object of our invention is to provide novel means for manipulating or moving eggs or rounded articles during a cleaning operation.

Another object of our invention is to provide egg cleaning mechanism wherein eggs of different size may be simultaneously and successively cleaned without interruption or alteration of the mechanism employed.

These and other objects and features of our invention will appear from the following description thereof in which reference is made to the figures of the accompanying drawings.

Fig. 1 is a vertical sectional view of a typical form of mechanism embodying our invention.

2

Fig. 2 is a plan view of the construction illustrated in Fig. 1.

Fig. 3 is a vertical sectional view of the construction shown in Fig. 1 taken on the line 3—3.

Fig. 4 is a plan view of the construction shown in Figs. 1 to 3 with the abrading means removed.

Fig. 5 is an enlarged view of a detail of the construction shown in Figs. 1 to 4.

Fig. 6 is a diagrammatic illustration of typical drive means for the mechanism shown in Figs. 1 to 5.

Fig. 7 is a diagrammatic side elevation of an alternative form of mechanism embodying our invention.

Fig. 8 is a vertical sectional view through a portion of the mechanism showing an alternative type of actuating means for the egg supporting members.

Fig. 9 is an end view of the egg supporting members with parts of the mechanism shown in section, and

Fig. 10 is an enlarged view of a detail of construction of an alternative form of egg engaging member.

25 In that form of our invention illustrated in Figs. 1 to 6 of the drawing, the mechanism is mounted on a support 2 which carries a motor 4 for driving the various elements of the device.

30 A pair of parallel article moving belts 6 extend longitudinally of the support 2 and pass about the pulleys 8 and 10 mounted on the rotatable shafts 12 and 14 respectively. Article holding bars 16 and spacing bars 18 are secured at their

35 opposite ends to the belts 6 and extend transversely across the machine beneath the lower runs 20 of a flexible abrading or cleaning means 22. The holding bars 16 and spacing bars 18 are spaced apart longitudinally of the belts 6 a distance sufficient to permit eggs or other articles to be cleaned or abraded to be carried longitudinally through the mechanism and to be tilted, oscillated or moved about during their travel without interfering with the movement of other articles preceding or following each other through the mechanism.

40 The eggs or other articles to be cleaned are supplied to the article moving means, including the belts 6 and the bars 16 and 18, at the delivery end 24 of the mechanism where a pair of inclined tracks 26 are arranged for receiving a number of eggs to feed them one after another to the article moving means. Any number of pairs of tracks 26 may be provided depending upon the capacity of the mechanism desired, but for purposes of illustration two pairs of tracks 26 are

45 50 55

shown. The eggs placed on these tracks roll down the same until they engage a stop member 28 carried by a rod 30. A weighted trip 32 is mounted on the end of the rod 30 and positioned adjacent on the outer face of the pulley 8 so that it will be engaged by the projecting end 34 of each of the egg holding bars 16 in turn as they are moved with the belts 6 in advancing the eggs through the mechanism. The trip 32 is raised by the projection 34 as the bar 16 moves beyond the next egg to be cleaned and the bar 18 moves into position to engage the foremost eggs on tracks 26 on release thereof. The projection 34 thus rotates rod 30 to move the stops 28 out of the way of the eggs on tracks 26 and the foremost eggs then roll forward into contact with the cushioned abutment member 36 and into position to be engaged by the spacing bar 18.

The belts 6 and bars 16 and 18 as well as the pulleys 8 are rotated in a clockwise direction as seen in Fig. 1 and the bars 16 and 18 therefore are moved upward as the upper runs of the belts 6 advance. The spacer bar 18 at the rear of the egg holding bar 16 then engages the eggs contacting the abutment member 36 and serve to raise and carry the eggs along through the mechanism beneath the lower run 20 of the abrading means 22. At the same time the projection 34 passes beyond the trip 32 so that the trip is released to fall back to a lowered position. In so doing the rod 30 is rotated to move the stop members into position to prevent the eggs from rolling forward so as to interfere with movement of the eggs by the bars 16 and 18. In this way the eggs are supplied successively to the mechanism and the foremost eggs from each track are picked up and advanced through the machine. At the same time the eggs are held in longitudinally spaced relation as they pass through the mechanism so as to be independently acted upon by the abrading or cleaning means employed.

The abrading means illustrated is in the form of a continuous length of flexible tape having grit or other abrading material carried by the face 38 thereof which contacts the articles 40 to be cleaned, polished or otherwise treated. The tape shown extends about the flanged pulleys 42 near the receiving end of the mechanism and about similar flanged pulleys 44 near the discharge end of the mechanism. The pulleys 42 and 44 are mounted for rotation with shafts 46 and 48 respectively and in practice the shafts 46 and 48 are sometimes machined to form the flanges of the pulleys integral therewith as a unit. When cleaning eggs the pulleys 42 and 44 are preferably positioned so that the lower runs 40 of the tape will extend longitudinally of the mechanism and be held in parallel relation. The upper runs 50 of the tape then extend diagonally as shown in Fig. 2 so as to be inclined the width of one pulley so that in passing continuously about the pulleys there is no tendency for the abrading means to thrust the articles diagonally or transversely of the machine. The surfaces of the pulleys 42 and 44 are preferably rounded or tapered slightly so as to center the tape and overcome the tendency of the tapes to slip sideways on the pulleys due to their angular relation with respect to the pulley shafts. The outermost strand of the tape on leaving the last flanged pulley of the delivery end of the mechanism extends upward to a roller 52, thence across the upper runs 50 as shown at 54 to a roller 56 on the opposite side of the

mechanism and then returns to the first flanged pulley on the opposite side of the mechanism at the receiving end thereof.

In this way a single continuous band, tape or strand of flexible material may be employed for cleaning or otherwise treating the articles, and the lower runs 20 of the abrading means may be caused to travel in parallel paths longitudinally of the mechanism. In the preferred operations, when cleaning eggs, the lower runs 20 all travel from the receiving end toward the discharge end of the mechanism at the same speed and in a direction parallel to the path of travel of the eggs so that the action of the tape or abrading means does not cause the eggs to be so displaced as to break or crack the shells. The construction shown and described also serves to maintain all of the strands engaging the articles under substantially the same tension so that there is no materially greater or different effect produced upon one part or in one area of the article being cleaned than in another. Uniform cleaning or treatment of the articles is thus assured. The tension applied to the strands as a whole may be controlled and maintained constant during any operation by mounting the rollers 52 and 56 on an arm 58 pivotally carried by the support 2 so as to be urged against the tape 54 by means of a spring 60 or other tensioning means.

A further advantage of the arrangement of the abrading means described results from the self threading character thereof when a change or replacement of the abrading means is necessary or desirable. At such times the tape is severed and an end of the new tape is attached to the end of the old tape. Thereafter, on operating the mechanism, the new tape is automatically drawn after the old one and threaded back and forth about the flanged pulleys 42 and 44 until the leading end of the new tape is brought back to its starting point. The ends of the new tape are then joined and the mechanism is immediately ready for renewed operation.

In order to insure cleaning, abrasion, brushing, polishing or other treatment of rounded articles throughout the entire surface thereof, and even when the articles are of irregular rounded shape, means are provided for tilting, oscillating or otherwise displacing the articles as they are moved lengthwise of the mechanism by the bars 16 and 18, and while they are in contact with the lower runs 20 of the flexible abrading means. For this purpose article supporting members 62, 64 and 66 are located below the article moving bars 16 and are arranged to cause the eggs or articles to be tilted laterally as they move from the receiving end of the mechanism to the delivery end thereof. The upper surfaces of the supporting members are cushioned and may be roughened or corrugated so as to present a non-slip surface which will prevent the eggs from rotating freely under the action of the abrading means. The eggs are positively tilted by relative vertical movement of the supporting members. For this purpose the members 62, 64 and 66 are each pivotally connected at 68 to the upper ends of the rocker arms 70. The lower ends of the rocker arms are pivotally connected to the cross rod 72 and eccentrics 74, 76 and 78 engage the rocker arms associated with the supporting members 62, 64 and 66 respectively. The eccentrics are secured to the rotatable shaft 80 and in practice the adjacent eccentrics are similar in form but displaced 180° on the shaft 80 so that

adjacent supporting members will be moved in opposite relation.

With this construction the supporting members cooperate to form tracks upon which the eggs are supported near their opposite ends. However, on rotation of the shaft 80 one supporting member is raised while the adjacent supporting member is lowered so that the eggs will be rocked back and forth as shown in Fig. 5. The eggs are thus moved from the full line position to the dotted line position one or more times during their passage through the mechanism, thereby presenting first one end and then the other end of the eggs to the action of the flexible strands forming the lower runs 20 of the abrading means. The rapidity of oscillation on rocking of the eggs may be varied considerably, but should be such as to assure effective cleaning of both ends of the eggs throughout the circumference thereof during a single passage through the mechanism from the delivery end to the discharge end.

The eggs are rolled forward on the supporting members by the forwardly moving lower runs of the abrading means but are held in predetermined position by the article holding bars 16. In order to facilitate transverse rocking or movement of the eggs while engaging the egg holding bars 16, these bars are provided with sleeves 82 which are spaced apart at their ends so that they may slide back and forth along the bars 16 and transversely of the mechanism with the tilting movement of the eggs. At the same time the sleeves are rotatable by the eggs so that the bars 16 present cushioned surfaces 84 which are freely movable with the eggs and impose no restriction to the movement thereof except in a longitudinal direction.

As the eggs approach the discharge end 86 of the mechanism, the holding bars 16 and spacing bars 18 move downward away from the abrading means as the belts 6 travel about the pulleys 10. The eggs are thus lowered into contact with the cushioned deflector 87 and roll off the holding bar 16 onto the tray 88. The opposite ends of the supporting members 62, 64 and 66 are preferably inclined downward as shown at 90 so as to provide for gradual movement of the eggs into and out of contact with the abrading means.

The operation of the mechanism shown in Figs. 1 to 6 and described above is as follows:

Eggs to be cleaned are charged onto the inclined tracks 26 and move forward by gravity into contact with the stop members 28 on the rod 30. They are preferably arranged so that the long axes of the eggs are parallel and therefore roll forward easily. The belts 6 are driven by motor 4 through shaft 12 and are moved so that the projecting end 34 of the egg holding bar engages and raises the trip 32 on bar 30. The stop members 28 are thus raised to permit the foremost eggs on the tracks 26 to roll forward and engage the abutment member 36. The stop member then drops back on release of the trip 32 to prevent other eggs on the tracks 26 from interfering with the operation of the mechanism. The eggs which have been released by the stop members are engaged and picked up by the spacing bars 18 and raised over the inclined ends 90 of the supporting members 62, 64 and 66 into positions behind the egg holding bars 16 and beneath the lower runs 20 of the abrading means.

The lower runs of the abrading means travel in a direction from the receiving end to the delivery end of the mechanism and engage the eggs so as to roll them forward into contact with the

cushioned sleeves 82 on the article holding bars 16. The eggs passing through the mechanism are thus held in longitudinally spaced relation permitting the flexible strands of the abrading means to engage each egg without being appreciably or materially deflected by a preceding or following egg. Furthermore, the eggs roll and turn about their longitudinal axes under the action of the abrading means and as they travel over the cushioned surfaces of the supporting members. In this way the eggs are rotated to present all sides of the eggs to the abrasive material on the lower face of the strands. At the same time free rotation of the eggs with the lower runs 20 is prevented by the cushioned upper surface of the supporting members along which the eggs roll. The abrasive material therefore brushes lightly over the relatively slow moving upwardly facing surfaces of the egg so as to clean the eggs effectively without danger or injury thereto. As shown in Fig. 5 the strands of abrasive material are positioned closely adjacent each other and are relatively narrow as compared with the length of the eggs. Therefore at least three strands engage the eggs at all times and they conform readily to the shape of the eggs in all positions during oscillation of the eggs.

During longitudinal movement of the eggs the supporting members 62, 64 and 66 are raised and lowered to tilt the eggs so that first one end and then the other end of each egg is presented to the abrading means insuring cleaning of the entire surface of each egg. When fully cleaned the eggs are discharged from the delivery end of the mechanism onto the tray 88 where they may be further inspected if desired and are presented ready for packing.

In the alternative form of the present invention shown in Figs. 7 to 10 of the drawing, the general assembly and organization of the elements is similar to that shown in Figs. 1 to 6. That is, the eggs to be cleaned are fed in at the inlet end of the mechanism and are moved over oscillating supports beneath and in contact with the moving abrading bands and are discharged from the outlet end of the mechanism. However many features of the construction illustrated in Figs. 7 to 10 differ from those in Figs. 1 to 6.

As shown in Fig. 7 the motor 100 for actuating the mechanism is mounted on frame 102 and is connected to a pulley 42' by the belt 104. The pulley 42' is engaged by the abrasive tape 22' which extends in a plurality of passes from the pulley 42' to the pulley 44'. The latter pulley is provided with a pinion 106 which drives a train of gears including the gear 108 and the gear 110.

Gear 108 is provided with four holes 112 which are spaced different radial distances from the center of the gear and a pin 114 is inserted in a selected one of the holes 112 and connected to one end of the link 116. The opposite end of the link 116 is connected to a bar 118 attached to the free ends of the two rocker arms 120. The rocker arms are attached to shafts 122 and 123 which extend transversely of the mechanism beneath the supporting members over which the eggs are moved.

Each of the shafts 122 and 123 is provided with arms 124 which are inclined to one side of a vertical plane passing through the shaft. Similarly arms 125 are secured to the shafts 122 and 123 and inclined to the opposite side of said plane. Rollers 126 are carried by the arms 124 and 125 and are positioned to bear against the lower surfaces of longitudinally extending bars 128 of egg

supporting members 129. The arms 124 on shafts 122 and 123 are in alignment lengthwise of the mechanism and the rollers 126 thereof engage opposite end portions of the same bar 128. In a like manner the arms 125 are in alignment and bear against the lower surfaces of the bars 128 of adjacent egg supporting members.

With this construction rotation of the gear 108 serves to actuate the link 116 to reciprocate rod 118 which in turn causes the rocker arms 120 to oscillate. The rocker arms when actuated cause the shafts 122 and 123 to rock back and forth whereby the oscillating arms 124 and 125 are moved through arcs which serve to raise and lower the egg supporting member. Because of the opposite inclination of the arms 124 and 125, adjacent egg supporting members are caused to move in opposite directions. Thus as one egg supporting member is raised those members on opposite sides thereof are lowered and thereafter when the first member is lowered the adjacent egg supporting members are raised. Egg engaging adjacent members 129 are thereby tilted back and forth transversely of the mechanism so that each end of every egg is presented to the flexible abrasive bands for cleaning as the eggs are carried longitudinally of the mechanism by the egg holding bars 16'.

The arc through which the rocker arms and oscillating arms 124 and 125 are moved and the distance that the egg supporting members are raised and lowered is determined by the position of the pin 114 with respect to the axis of the gear 108. By moving the pin 114 from one hole 112 to another the amplitude of movement of the rocker arms 120 and oscillating arms 124 and 125 may be varied so that the egg supporting members may be raised and lowered through the desired distance to insure proper tilting and cleaning of the eggs.

The egg supporting members as shown in Figs. 8 and 9 consist of the flexible cushioning members 130 which are preferably formed of rubber and provided with longitudinally extending ribs or ridges 132 which serve to engage and hold the eggs in a manner which prevents free rotation or spinning of the eggs under the action of the abrasive bands engaging the upper portions of the eggs. The cushioning members 130 are sufficiently flexible so that they bend readily beneath the eggs as shown in Fig. 9 and yieldably urge the eggs upward against the flexible strips of abrasive material. The eggs are thus lightly but firmly held on a cushioned support which allows movement of the eggs without permitting them to bounce or have free movement at any time during the cleaning operation.

The bar 128 of the egg moving members is provided with a vertically extending tubular member 134 adjacent each end thereof. The tubular members 134 receive pins 136 which project upwardly from the transverse stationary supports 138. Therefore when the oscillating arms 124 and 125 are rocked, the egg supporting members are moved vertically but are held against longitudinal movement and therefore do not influence or affect the forward movement or rotation of the eggs as they travel over the cushioning members 130.

The eggs are moved longitudinally of the egg supporting members by rotation of the gear 110 which drives the belt 6' carrying the egg holding bars 16' and the spacing bars 18'.

As shown in Fig. 10 the bars 16' and 18' are provided with flat egg engaging members 140.

The members 140 engage the eggs being moved through the mechanism and in this respect replace the rotatable collars 82 carried by the holding bars 16 of the construction shown in Figs. 1 to 6. It is found in practice that by using such flat egg engaging members the eggs are allowed to oscillate freely regardless of the size of the egg and there is no danger of even a large egg being carried over the holding bar 16' as it oscillates and rotates during the cleaning operation. The vertical width of the engaging members 140 is preferably as great as possible without interfering with the movement of the egg supporting members and abrasive bands.

The manner of operation and movement of the elements of the mechanism shown in Figs. 7 to 10 will be apparent from the foregoing discussion of the operation of the device shown in Figs. 1 to 6. It will also be apparent that one or more of the alternative elements shown in Figs. 7 to 10 may be embodied in the construction of Figs. 1 to 6. Thus for example the egg supporting members of the construction shown in Fig. 1 may be replaced by the egg supporting member 132 and the oscillating means therefor shown in Figs. 7 and 8.

The speed of movement of the various elements of the mechanism may be altered as desired to obtain the best results, but when cleaning eggs it is generally preferable to avoid polishing the surfaces in order that the eggs will present a natural dull appearance. The speed of travel of the lower runs of the abrasive tape may be from about 350 to 800 feet per minute but higher or lower speeds may be used. Similarly, the speed of travel of the eggs through the mechanism and the rapidity with which they are tilted may be varied but in practice the eggs usually are submitted to an abrading operation lasting from about 20 seconds to one minute.

The treatment of the eggs is so gentle that even cracked eggs have been cleaned successfully, but the mechanism may be adjusted and the type of abrading means employed may be varied so as to give more vigorous treatment to articles for brushing, polishing or cleaning purposes. In view thereof it should be understood that the construction and arrangement of the elements may be changed and their manner of operation varied in many ways for treating other articles and without departing from the spirit and scope of our invention. It should therefore be understood that the particular embodiments of our invention herein shown and described are intended to be illustrative only and are not intended to limit the scope of our invention.

This application is a continuation of our pending application Serial No. 683,721 filed July 15, 1946, now abandoned, entitled Article Cleaning Mechanism.

We claim:

1. Mechanism for cleaning rounded articles comprising article supporting means, means for moving articles to be cleaned longitudinally of said mechanism and along said article supporting means, a continuous band of flexible cleaning material having a portion thereof spaced from said supporting means a distance less than the diameter of the articles to be cleaned so as to be positioned to engage articles on said support, means for moving the article engaging portion of said flexible band longitudinally of said mechanism, and means for rotating said articles about an axis extending longitudinally of said mechanism while the articles are engaged by said portion of the flexible band.

2. Mechanism for cleaning rounded articles comprising article supporting means, means for moving articles to be cleaned longitudinally of said mechanism and along said article supporting means, a continuous band of flexible cleaning material having a portion thereof spaced from said supporting means a distance less than the diameter of the articles to be cleaned so as to be positioned to engage articles on said support, means for moving the article engaging portion of said flexible band in the same direction but at a higher speed than said articles, and means for rotating said articles about an axis extending longitudinally of said mechanism while the articles are engaged by said portion of the flexible band.

3. Mechanism for cleaning rounded articles comprising article supporting means, means for moving articles to be cleaned longitudinally of said mechanism and along said article supporting means, a continuous band of flexible cleaning material having a portion thereof spaced from said supporting means a distance less than the diameter of the articles to be cleaned so as to be positioned to engage articles on said support, means for moving the article engaging portion of said flexible band in the same direction but at a higher speed than said articles, and means for oscillating said articles during their travel through said mechanism.

4. Mechanism for cleaning rounded articles comprising article supporting means defining a path of travel for articles to be cleaned, means for successively moving articles along said article supporting means, flexible article cleaning means spaced from said article supporting means a distance less than the diameter of the articles to be cleaned and extending generally parallel to the path of travel of said articles so as to be positioned to engage articles moving along said supporting means, and means for tilting the articles during their movement along said path.

5. Mechanism for cleaning rounded articles comprising article supporting means defining a path of travel for articles to be cleaned, means for successively moving articles along said article supporting means, flexible article cleaning means spaced from said article supporting means a distance less than the diameter of the articles to be cleaned and extending generally parallel to the path of travel of said articles so as to be positioned to engage articles moving along said supporting means, means for moving said article cleaning means in the same direction but at a higher speed than the articles to be cleaned, and means for tilting the articles during their movement along said path.

6. An egg cleaning machine comprising a plurality of egg cleaning means in the form of flexible abrasive strands each having a predetermined width less than one-third the longitudinal length of an egg to be cleaned, egg supporting means positioned to receive and support an egg and spaced from said abrasive means a distance less than the diameter of the eggs to be cleaned, means for moving said strands with respect to said egg supporting means, and means for oscillating said egg supporting means.

7. An egg cleaning machine of the character set forth in claim 6 wherein the strands of the egg cleaning means which engage an egg extend parallel to each other and are connected together to form a single continuous band.

8. Mechanism for cleaning eggs comprising a pair of parallel egg supporting members, means for moving eggs longitudinally of said members,

flexible egg cleaning means extending generally parallel to said members and having a portion thereof engagable with eggs on said supporting members, means for moving said cleaning means in the same direction but at a faster speed than said eggs, and means for moving said supporting members relative to each other to tilt said eggs.

9. Mechanism for cleaning eggs comprising a pair of parallel egg supporting members, means for moving eggs longitudinally of said members, flexible egg cleaning means extending generally parallel to said members and having a portion thereof engagable with eggs on said supporting members, means for moving said cleaning means in the same direction but at a faster speed than said eggs, and means for alternately moving said supporting members toward and away from said egg cleaning means to tilt the eggs during their passage through said mechanism.

10. Mechanism for cleaning eggs comprising a support over which the eggs are movable through the mechanism, flexible egg cleaning means extending longitudinally of said support and having a portion thereof engagable with eggs on said support, means for moving said portion of the cleaning means longitudinally of the mechanism, means for moving eggs over said support including longitudinally spaced members located between said support and cleaning means and engageable by the eggs to limit movement thereof under the action of said cleaning means, and means for moving said spaced members longitudinally of the mechanism.

11. Mechanism for cleaning eggs comprising a pair of members positioned to support the opposite ends of eggs moving through the mechanism, flexible egg cleaning means extending generally parallel to said supporting members and having portions thereof engagable with eggs on said supporting members, means for moving said cleaning means longitudinally of said supporting members and with respect to eggs thereon, means for moving said supporting members in opposite directions to oscillate the eggs thereon, and an egg holding member located between said supporting members and cleaning means and movable longitudinally of said mechanism for controlling the speed of movement of said eggs through the mechanism.

12. Mechanism for cleaning eggs comprising a pair of members positioned to support the opposite ends of eggs moving through the mechanism, flexible egg cleaning means extending generally parallel to said supporting members and having portions thereof engagable with eggs on said supporting members, means for moving said cleaning means longitudinally of said supporting members and with respect to eggs thereon, means for moving said supporting members in opposite directions to oscillate the eggs thereon, egg holding means located between said members and said cleaning means in position to be engaged by said eggs, means for moving said egg holding means longitudinally of said mechanism, and transversely movable bearing elements on said egg holding means movable with said eggs during oscillation thereof.

13. Mechanism for cleaning eggs comprising a pair of members positioned to support the opposite ends of eggs moving through the mechanism, flexible egg cleaning means extending generally parallel to said supporting members and having portions thereof engagable with eggs on

said supporting members, means for moving said cleaning means longitudinally of said supporting members and with respect to eggs thereon, means for moving said supporting members in opposite directions to oscillate the eggs thereon, egg holding means located between said members and said cleaning means in position to be engaged by said eggs, means for moving said egg holding means longitudinally of said mechanism, said egg holding means presenting a substantially flat surface extending normal to said egg supporting members and engagable by the eggs during oscillation thereof.

14. Egg cleaning mechanism comprising cleaning means in the form of a single band of abrasive material arranged in a series of adjacent loops so as to provide a plurality of parallel strands of flexible material each presenting an abrasive surface for engagement by the eggs to be cleaned, the opposite ends of said band being connected together to form a continuous belt, means for moving said strands in the same direction and at the same speed, means for maintaining all of said strands under substantially the same tension, egg supporting means extending parallel to said strands and spaced therefrom a distance less than the diameter of the eggs to be cleaned, and means for moving eggs to be cleaned over said supporting means into and out of contact with the abrasive surfaces of said strands.

15. Egg cleaning mechanism comprising cleaning means in the form of a plurality of parallel strands of flexible material each presenting an abrasive surface for engagement by the eggs to be cleaned, means for moving said strands in the same direction and at the same speed, egg supporting means extending parallel to said strands and spaced therefrom a distance less than the diameter of the eggs to be cleaned, means for moving eggs to be cleaned over said supporting means into and out of contact with the abrasive surfaces of said strands, and means for oscillating the eggs while in contact with said strands and supporting means.

16. Mechanism for cleaning rounded articles comprising an article support, flexible abrasive means, means for moving said abrasive means with respect to said article support, said abrasive means and article support being located in substantially parallel planes and spaced apart a distance less than the diameter of the articles to be cleaned, and means for positively moving articles along said support through the space between the support and abrasive means whereby the abrasive means serve to hold the articles in contact with said support during movement of the articles to be cleaned.

17. An egg cleaning device comprising egg supporting means extending longitudinally of the device, means for moving eggs longitudinally of the device in engagement with said egg supporting means, cleaning elements located adjacent said egg supporting means in position to engage eggs located on the upper surface of said egg supporting means, means for moving said cleaning elements with reference to said egg supporting means, and means for oscillating said egg supporting means during the travel of eggs longitudinally of said device.

18. Egg cleaning mechanism comprising egg supporting means extending longitudinally of the mechanism, means for directing eggs to be cleaned onto the upper surface of said supporting means near one end thereof, means for moving eggs longitudinally of said mechanism on the upper surface of said supporting means, means located near the other end of said egg supporting means for receiving cleaned eggs therefrom, egg cleaning means located between said egg directing means and said egg receiving means and including a plurality of flexible abrasive elements arranged to engage eggs located on said egg supporting means, means for moving said abrasive elements with reference to said egg supporting means and any eggs thereon, and means for moving said egg supporting means to tilt eggs thereon during the travel of eggs from said egg directing means to said egg receiving means.
